US0D1018839S

(12) **United States Design Patent** (10) **Patent No.:** **US D1,018,839 S**
(45) **Date of Patent:** **** Mar. 19, 2024**

(54) **TAMPON**

(71) Applicant: **Tampro Inc.**, San Francisco, CA (US)

(72) Inventors: **Greta Catherine Meyer**, San Francisco, CA (US); **Amanda Paige Calabrese**, San Francisco, CA (US); **Elijah John Sampson Zenger**, New York, NY (US)

(73) Assignee: **Tampro Inc.**, San Francisco, CA (US)

(**) Term: **15 Years**

(21) Appl. No.: **29/869,156**

(22) Filed: **Dec. 22, 2022**

Related U.S. Application Data

(63) Continuation of application No. 29/725,737, filed on Feb. 26, 2020, now Pat. No. Des. 977,632.

CLAIM

The ornamental design for a tampon, as shown and described herein.

DESCRIPTION

FIG. 1 is a top perspective view of a tampon showing our design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines shown in the drawings represent portions of the tampon that form no part of the claimed design.

1 Claim, 7 Drawing Sheets
